[57] CLAIM

The ornamental design for a combined scraper, refinishing tool, wall paper tool and chisel, as shown and described.

DESCRIPTION

FIG. 1 is a top plan view of a combined scraper, refinishing tool, wall paper tool and chisel, showing my new design;

FIG. 2 is a left side elevational view, the right side being a mirror image thereof;

FIG. 3 is a bottom plan view thereof;

FIG. 4 is a left end elevational view thereof;

FIG. 5 is a right end elevational view thereof;

FIG. 6 is a top plan view with the chisel extended for use;

FIG. 7 is a side elevational view thereof.
